UNITED STATES PATENT OFFICE.

RUDOLF E. HELLMUND, OF PITTSBURGH, PENNSYLVANIA, ASSIGNOR TO WESTINGHOUSE ELECTRIC AND MANUFACTURING COMPANY, A CORPORATION OF PENNSYLVANIA.

SUPPLY SYSTEM FOR PULSATING-TORQUE MOTORS.

1,276,914.

Specification of Letters Patent. Patented Aug. 27, 1918.

Application filed May 20, 1916. Serial No. 98,786.

To all whom it may concern:

Be it known that I, RUDOLF E. HELLMUND, a subject of the Emperor of Germany, and a resident of Pittsburgh, in the county of 5 Allegheny and State of Pennsylvania, have invented a new and useful Improvement in Supply Systems for Pulsating-Torque Motors, of which the following is a specification.

10 My invention relates to systems of current supply for pulsating-torque motors, having relation particularly to motors of the single-phase, commutator type, and it has for its object to provide means whereby a load 15 may be driven with a substantially uniform torque by means of motors of the character indicated.

Other objects of my invention are to provide means whereby the commutation and 20 power factor of motors of the character designated may be adjusted for desirable operation.

In the accompanying drawing, Figure 1 is a diagrammatic view of two alternating-current motors of the single-phase, cross-field, commutator type, together with their attendant supply circuits, illustrating one 25 form of my invention; Fig. 2 is a vector diagram illustrating the relation of the current 30 and voltage vectors in the system of Fig. 1; Figs. 3, 4, 10 and 11 are diagrammatic views of modifications of the system shown in Fig. 1; Figs. 5, 6, 7 and 8 are simplified diagrammatic views illustrating the development of 35 the connections shown in Fig. 4; Fig. 9 is a sequence chart illustrating the order of operation of the switches of Fig. 4 in order 40 to produce the acceleration indicated in Figs. 5 to 8, inclusive; Figs. 12, 13 and 15 45 are diagrammatic views of systems embodying my invention and applied to a larger number of motors, such, for example, as four; Figs. 14 and 16 are sequence charts setting forth the preferred order of switch 50 operation in the systems of Figs. 13 and 15; and Figs. 17 and 18 are detail views illustrating preferred forms of mounting the phase-adjusting inductive devices of Fig. 15.

It is a well known fact that the energy 55 of a single-phase system is pulsating in char-

acter so that the torque developed by a single-phase alternating-current motor is necessarily pulsating. The effects of said pulsating torque may be greatly reduced by the fly-wheel action of the rotor and of 55 other moving parts but, nevertheless, there still remains a perceptible vibratory action which may have a harmful effect upon the operation of a railway vehicle. By my invention, I mechanically couple two or more 60 motors of the character indicated to a single load shaft and I then provide means whereby the electromotive forces supplied to said motors are caused to differ perceptibly in phase, whereby the torques of the different motors maintain a distinct phase displacement from each other and the resultant torque supplied to said load is accordingly 65 substantially uniform in character. Theoretically, in applying my invention to two 70 motors, it would be necessary to maintain a phase relation of substantially 90° between the two motor torques in order to obtain a substantially uniform resultant torque but in practice, I find that a much smaller phase divergence than that indicated produces a sufficiently beneficial effect upon the operation. 75

The phase displacement between the electromotive forces supplied to different motors may be provided by a phase converter of the 80 rotary type associated with a single-phase supply source. Furthermore, by providing said phase converter with a direct-current exciting winding for synchronous operation, a power-factor-correcting action may be applied to the motors by adjusting the strength 85 of direct-current excitation, in a well known manner.

The pulsating torque effects of the two 90 motors may be still further eliminated and a more nearly uniform torque supplied to a driving axle by the mechanical storage and release of energy obtained by inserting a resilient connection between each rotor and the axle. 95

Referring to the drawing for a more detailed understanding of my invention, I show two motors of the single-phase, cross-field, commutator type at 1 and 2 in Fig. 1. The motor 1 is provided with an ar- 100

ture 3, an exciting field winding 4, and an inducing-field winding 5 and, in like manner, the motor 2 is provided with an armature 6, an exciting-field winding 7 and 5 with an inducing-field winding 8. Energy for the operation of the motors 1 and 2 is derived from any suitable source, such, for example, as the secondary winding 9 of a transformer 10. While I have shown the 10 transformer 10 as of the double-winding type, it may if desired, be an auto-transformer and be energized by connection between a trolley and ground, as is usual in railway work, or by any other desired means. The 15 motors 1 and 2 are connected in series relation across the supply winding 9 in accordance with the well known doubly-fed system, the cross-field windings 5 and 8 being connected respectively between the 20 outer terminals of the supply winding 9 and suitable adjustable intermediate tap connections 11 and 12. A phase converter 13 of the rotary type has its primary winding 14 connected across the supply winding 9 and has its secondary winding 15 connected between substantially the mid point of the supply winding 9 and a point 16 between the two motors 1 and 2. The rotor of the phase converter 13 is preferably provided 25 with a squirrel cage winding 17 and with an exciting winding 18 which may be energized from a suitable direct-current source 19 through the usual slip rings. The armatures 3 and 6 are mounted on the same 30 shaft 20 and resilient couplings 21-21, such, for example, as are shown in Fig. 2 of U. S. patent to Priest 508,634, November 14, 1893, are preferably inserted therebetween for torque equalization.

40 Having thus described the arrangement of a system embodying my invention, the operation is as follows: The motors 1 and 2 are started and accelerated in any desired manner, and the machines 13 and 19 are also 45 started and operated by any desired means, the specific instrumentality employed for this purpose forming no part of the present invention. The system thus being in operation, the voltages $E_{1\text{aux}}$ and $E_{2\text{aux}}$ impressed 50 upon the two cross-field windings 5 and 8 may be represented by corresponding vectors in Fig. 2. In like manner, the transformer voltage impressed upon the armature 8 and main-field winding 4 may be indicated 55 by a vector e_1 and that impressed upon the armature 6 and main field winding 7 by a vector e_2 . The voltage generated in the secondary winding 15 of the phase converter is substantially 90° out of phase with 60 the electromotive force of the source 9 and may be indicated by a vector E . The resultant voltage upon the armature 3 and the main field winding 4 is indicated by a vector E_1 and that impressed upon the armature 6

and the main field winding 7 by a vector E_2 . 65 The current of the motor 1 is indicated by a vector I_1 , lagging behind the corresponding electromotive force by an angle A , and, in like manner, the current of the motor 2, indicated by a vector I_2 lags behind the corresponding electromotive force E_2 . The vector sum of the currents I_1 and I_2 is the phase converter current I , lagging behind the voltage E by the same angle A . 70

75 It will be noted that there is an appreciable phase difference between the resultant voltages E_1 and E_2 impressed upon the two motors and there is accordingly a phase difference between the pulsating torques thereof which is sufficient to produce a substantially uniform torque in the shaft 20. The capacity of the phase converter is equal to the product EI , whereas the total motor capacity is proportional to $(E_{1\text{aux}}+E_1)(I_1)(\cos A)+(E_{2\text{aux}}+E_2)(I_2)(\cos A)$. 80 It is therefore possible to produce a marked difference in the phase of the currents I_1 and I_2 with a phase converter capacity of only a small percentage of the main motor capacity. 85 If the phase converter is utilized at the same time for driving auxiliary apparatus, such as air blowers and compressors, it entails but small additional expense over the customary locomotive equipment.

90 The adjustment of the direct-current excitation of the rotor of the phase converter 13 from the source 19 produces substantially no effect upon the phase conversion but may be caused to produce leading current for supply to the source 9 to neutralize the lagging current caused by the leakage flux, etc., 95 in the motors 1 and 2.

100 Another advantage of the structure shown is that the small phase difference indicated between the auxiliary and armature voltages in each machine is beneficial to the commutation, causing the electromotive force produced by the rotation of the short circuited armature conductors undergoing 105 commutation in the cross field to more nearly neutralize the joint effects of transformer and reactance electromotive forces therein.

110 The objectionable effects of pulsating motor torque are much more noticeable at starting than during full-speed operation and, furthermore, the commutation problem is in general more difficult at starting than during the latter stages of motor acceleration. For both of these reasons, it may be advisable to maintain the phase converter in circuit only during the starting steps, eliminating the same during full-speed operation and thus permitting the use of a still smaller phase converter to produce a given phase-shifting effect. 115

120 In the system of Fig. 1, I have shown both motors as provided with main and with

cross-field windings but it is not only feasible but desirable to combine the two cross-field windings into a single winding, as shown in Fig. 3 wherein the connections in general are as shown in Fig. 1 with the exception that a single cross field winding 22 is mounted to act upon both armatures. The specific details of a twin motor embodying this construction, form no part of this invention but are separately shown and claimed in my copending application, Serial No. 76,152, filed February 4, 1916, and in a copending application of Rudolf E. Hellmund and Ralph E. Ferris, Serial No. 75,932, filed February 3, 1916, and assigned to the Westinghouse Electric & Manufacturing Company. Neither of said applications, however, disclose the use of a phase converter for producing phase displacement in the applied voltages and torques of the two elements of the twin-motor combination.

The motors of a system embodying my invention may be started and accelerated in any of the well known manners indicated in an article by R. E. Hellmund and J. V. Dobson, entitled "The single-phase commutator motor" appearing on page 112 *et seq.* of the "Electric Journal" for March 1916, but I preferably start said motors as repulsion machines, with the armatures short circuited through resistance members, and thereafter accelerate them as doubly-fed motors, as indicated in Figs. 4 to 9, inclusive. As the specific method of acceleration forms no part of the present invention, the same will be described but briefly. At the outset, the two motors are connected for repulsion operation, with the resistors inserted in the armature short circuits, (Fig. 5), intermediate taps being then established (Fig. 6), the repulsion connections removed (Fig. 7) and the armature voltages raised (Fig. 8).

Fig. 10 shows the application of my invention to motors in which the main field windings are energized by the difference between the armature and cross field currents rather than by being energized by the armature current.

A phase-displacing effect similar to that produced by a phase converter may be produced by an inductive winding, with the disadvantage, however, that lagging power-factor correction is not possible. A system embodying this modification of my invention is shown in Fig. 11. Two motors 1 and 2 are connected to derive energy from a supply winding 9, and said motors are of different capacity, the motor 1 being larger than the motor 2. An inductive winding 41 is inserted in a connection from a point between the two motors to an intermediate point in the source, and the excess of load current of the motor 1 over that of the motor 2 flows therethrough. Thus, the sup-

ply circuit of the large motor 1 is more highly inductive than that of the small motor 2 and the current therein therefore lags a greater amount, producing the desired phase displacement between the torques of the two motors.

It is usual to supply electrical propelled vehicles, such, for example, as cars and locomotives, with four main motors and I show an installation of this type embodying my invention in Fig. 12. Four motors, or rather two twin motors, of the single-phase, cross-field, commutator type are designated, respectively, as 42, 43, 44 and 45. The motors 42 and 44 are mounted on one shaft and the motors 43 and 45 are mounted on another. An intermediate connection to the source 9 includes an inductive device 41 for phase conversion, as in the system of Fig. 11. The armature windings of the motors 42 and 43 are connected in parallel to each other between the intermediate tap 11 and the lower end of the reactor 21. The armature of the motor 44 is connected between an intermediate tap 12 and the lower end of the reactor 41, whereas the armature of the motor 45 is connected between the intermediate tap 12 and the upper end of the reactor device 41, the exciting-field windings of the respective motors being connected in series with their associated armatures. Thus, the power factors of the various armature circuits differ, and there is a phase difference between the armature currents of the armatures 42, 44 and 43 and 45, respectively, resulting in the production of substantially uniform torque in the two shafts.

Figs. 13 and 14 indicate a preferred mode of acceleration to be employed on locomotives embodying two or more pairs of twin motors. The system is of the general character indicated in Fig. 12, with the exception that a rotary phase converter is employed for torque displacement rather than the reactance device of Fig. 12. As indicated in the sequence chart of Fig. 14, the motors are all started as repulsion motors and are subsequently changed over for doubly-fed acceleration, with a rising armature impressed voltage derived from an adjustable intermediate tap.

Figs. 15, 16, 17 and 18 relate to a similar system, with the exception that the motors are started in a doubly-fed connection and the main fields are weakened by means of shunting inductance coils 66 and 67 in order to reduce the transformer action of the heavy starting current flowing in the main field windings upon the short circuited armature coils undergoing commutation. The two impedance coils 66 and 67 are preferably wound upon the same magnetic core, as shown in Figs. 17 and 18, for the purpose of equalizing the load between the different

1
motors, and said magnetic cores are preferably provided with incomplete magnetic circuits, as shown, in order to increase the leakage flux and, therefore, the inductive effect of the windings 66 and 67.

5 I claim as my invention:

10 1. The combination with two, single-phase, alternating-current motors of the commutator type, of a resilient mechanical coupling between the rotors thereof, and means for maintaining a phase difference between the electromotive forces applied to the two motors.

15 2. The combination with two, single-phase, alternating-current motors of the cross-field, commutator type, of a resilient mechanical coupling between the motors thereof, and means for maintaining a phase difference between the electromotive forces applied to the armature windings of the two motors.

20 3. The combination with a source of single-phase, alternating-current, of two single-phase, alternating-current motors connected in series relation across a portion thereof, a connection from a point between said motors to an intermediate point in said source, and phase-displacing energy-storing and restoring means in said connection.

25 30 4. The combination with a source of single-phase, alternating current, of two, single-phase, alternating current motors connected in series relation across a portion thereof, a mechanical coupling between the rotors thereof, a connection from a point between said motors to an intermediate point in said source, and phase-displacing energy-storing and restoring means in said connection.

35 40 5. The combination with a source of single-phase, alternating current, of two single-phase, alternating current motors connected in series relation across a portion thereof, a resilient mechanical coupling between the rotors thereof, a connection from a point between said motors to an intermediate point in said source, and means for generating an alternating electromotive force in said connection differing in phase from the electromotive force of the main source.

45 55 6. The combination with a source of single-phase, alternating current, of two single-phase, alternating-current motors of the commutator type connected in series relation across a portion thereof, a resilient mechanical coupling between the rotors thereof, a connection from a point between said motors to an intermediate point in said source, and means for generating an alternating electromotive force in said connection differing in phase from the electromotive force of the main source.

60 7. The combination with a source of alternating current, of two alternating-cur-

rent motors connected in series relation 65 across a portion thereof, mechanical coupling means between the rotors of said motors, a connection from a point between said motors and an intermediate point in said source, and a dynamo-electric phase-converter arranged to produce an electromotive force in said connection of like frequency to the electromotive force of the source but differing therefrom in phase.

70 75 8. The combination with a source of alternating current, of two alternating-current motors connected in series relation across a portion thereof, resilient mechanical coupling means between the rotors of said motors, a connection from a point between said motors and an intermediate point in said source, and a phase converter arranged to produce an electromotive force in said connection of like frequency to the electromotive force of the source but differing therefrom in phase.

80 85 9. The combination with a source of alternating current, of two alternating-current motors connected in series relation across a portion thereof, mechanical coupling means 90 between the rotors of said motors, a connection from a point between said motors and an intermediate point in said source, and a phase-converter having its primary winding connected to said source and having its secondary winding inserted in said connection, whereby an electromotive force is induced in said intermediate connection of like frequency to the electromotive force of said source but differing therefrom in phase.

95 100 10. The combination with a source of alternating current, of two alternating-current motors connected in series relation across a portion thereof, resilient mechanical coupling means between the rotors of 105 said motors, a connection from a point between said motors and an intermediate point in said source, and a phase-converter having its primary winding connected to said source and having its secondary winding inserted 110 in said connection, whereby an electromotive force is induced in said intermediate connection of like frequency to the electromotive force of said source but differing therefrom in phase.

105 110 11. The combination with a source of alternating current, of two alternating-current motors connected in series relation across a portion thereof, mechanical coupling means between the rotors of said motors, a connection from a point between said motors and an intermediate point in said source, and a synchronous phase-converter arranged to produce an electromotive force in said connection of like frequency to the 115 electromotive force of the source but differing therefrom in phase and means for varying the amount of direct current excitation

of said phase converter, whereby the power factor of the load on said main source may be adjusted.

12. The combination with a plurality of 5 single-phase, alternating-current motors of the commutator type, each of which embodies an armature and a main field winding, of means for supplying current of dif-

fering phase to said armatures, a common cross field winding magnetically associated 10 with all of said armatures and exciting means therefor.

In testimony whereof I have hereunto subscribed my name this 29th day of April, 1916.

RUDOLF E. HELLMUND.
